UNITED STATES PATENT OFFICE.

CHARLES G. CURTIS, OF NEW YORK, N. Y., ASSIGNOR, BY MESNE ASSIGNMENTS, TO CURTIS STEAM TURBINE COMPANY, A CORPORATION OF WEST VIRGINIA.

ELASTIC-FLUID TURBINE.

SPECIFICATION forming part of Letters Patent No. 727,912, dated May 12, 1903.

Application filed July 31, 1897. Serial No. 646,625. (No model.)

To all whom it may concern:

Be it known that I, CHARLES G. CURTIS, a citizen of the United States, residing at New York city, in the county and State of New York, have invented a certain new and useful Improvement in Elastic-Fluid Turbines, of which the following is a specification.

The object I have in view is to provide means for reversing compound elastic-fluid turbines, such as are described in my Patents Nos. 566,968 and 566,969, and particularly for reversing compound elastic-fluid turbines comprising each two or more sections (each section being simple or compound) inclosed in separate fluid-tight shells and connected in succession with two or more expansion-nozzles, whereby the elastic-fluid pressure is converted into *vis viva*, and the *vis viva* is utilized in stages, such as described in my said Patent No. 566,969. To accomplish the reversing of the turbine, I construct each wheel or revolving portion of my turbine so that it is provided with one or more additional annular ranges of vanes or buckets, which are set in the opposite direction to the regular vanes or buckets. This additional set of vanes coacts with an additional nozzle, (preferably of the expansion type,) which is set in the opposite direction to the regular nozzle, and the jet of steam or other elastic fluid delivered by which causes the turbine to rotate in the reverse or backward direction. Where the turbine is composed of two or more sections, each inclosed in a separate fluid-tight shell and having intermediate passages between the shells terminating in delivery-nozzles, preferably of the expansion type, the additional reversing-vanes will be provided in each section, and suitable intermediate passages and delivery-nozzles will be provided to coöperate with these reversing-vanes. Where the turbine is compounded in each shell or is one of a single shell with a compound wheel, stationary as well as rotating reversing-vanes will be provided corresponding with the vanes for producing forward motion.

Although the vanes for producing forward motion may be unsymmetrical in shape and

preferably are in my turbine, I make the movable reversing-vanes of symmetrical form or regularly curved from the center in both directions, so that there will be no tendency for the reversing-vanes to have a fan-like action when the turbine is being driven forward, as they would have if made unsymmetrical like the regular vanes, causing a large circulation of fluid through these vanes, and thus resulting in a loss of power.

I provide the passages with suitable valves by which the elastic-fluid jet is caused to pass through one set of passages or the other throughout the system of vanes and stationary passages, and thus cause the turbine to rotate in a forward or backward direction. The several valves controlling each set of passages may be connected together so as to be worked simultaneously, the motion being preferably produced by a cylinder and piston forming a power-relay.

The drawing illustrates, largely in diagram, a turbine embodying the invention.

A, B, and C are three wheels inclosed in separate fluid-tight shells D, as described in my Patent No. 566,969. Each wheel may be simple or compound, as described in said patent. As shown, each wheel is provided with a single set of rotating vanes *a* for producing forward motion. These are of unsymmetrical curved form, as described in my Patent No. 566,968. Arranged around the circumference of each wheel, but within the vanes *a*, is a second set of vanes *b*, which are set in the opposite direction to the vanes *a* and are preferably of symmetrical curved form, as shown. Expansion-nozzles E F G coöperate with the vanes *a*, while similar expansion-nozzles H I J, set in the opposite direction, coöperate with the vanes *b*. A separate set of valves may be used for controlling each set of nozzles, or, as shown in the drawing, one set of valves may be used to control both sets of nozzles. To accomplish this, a pipe *c* leads into a valve-chamber *d*, with opposite ends of which the nozzles E and H are connected by suitable pipes *e f*. The pipe *c* is provided with a suitable throttle-valve, (not shown,) which is used to shut off steam from the en-

tire engine when not running. A piston-valve K moves between valve-seats *g h* in the opposite ends of chamber *d* and is connected with a valve-rod *i*, passing out through a 5 stuffing-box *j*. In the central position of the valve K it covers the opening of the pipe *c* into the valve-chamber *d* and shuts off the supply of steam to both nozzles E and H. When the valve K is moved to the right and 10 is seated on the seat *h*, steam is admitted to the nozzle E, which delivers a steam-jet to the vanes *a* for driving the turbine forward. Steam is at this time cut off from the reversing-nozzle H. When the valve K is moved 15 to the left and is seated on the seat *g*, the steam is cut off from the nozzle E and is admitted to the nozzle H, which delivers a jet to the reversing-vanes *b*. The valve-seats *g h* make a tight fit with the valve and insure a 20 steam-tight closing of the valve.

The exhaust from the wheel A, whether the jet is delivered by the nozzle E or H, is received by a steam-box L, which covers the discharging ends of enough of both sets of 25 vanes *a* and *b* to receive all the steam delivered by either nozzle. From the steam-box L a pipe *c'* leads to a valve-chamber *d'*, in which moves a piston-valve K' and with the opposite ends of which are connected the nozzles F and I. These nozzles are larger in 30 cross-sectional area than the nozzles E and H to accommodate the increased volume of the steam-jet and the pipe *c'*. Valve-chamber *d'* and valve K' are similarly larger than the 35 corresponding parts *c*, *d*, and K. A steam-box L' receives the steam from the vanes of the wheel B, and parts *c'*, *d'*, and K', similar to *c*, *d*, and K, but larger, connect the steam-box L' with the nozzles G and J, which are 40 larger than the nozzles F and I and coact with the vanes *a b* of the third wheel C. The discharge from the wheel C is received by a steam-box L², which may be connected with a fourth wheel, if one is used. If only three 45 wheels are used, the steam-box L² discharges into the air for a non-condensing engine or into a condenser or other means for producing less than atmospheric pressure, if the engine is a condensing-engine.

50 The valve-rods *i*, *i'*, and *i''* of the valves K K' K² are connected with a rod *k* by means of gear-wheels *l*. This rod *k* is connected with the piston of a steam-relay M, by means of which the valves K K' K² can be operated simultaneously.

What I claim is—

1. In an elastic-fluid turbine, the combination with movable direct vanes for producing forward motion, of two or more sets of movable reverse vanes and intermediate guide-passages through which the fluid passes in succession for producing backward motion, and an expansion-nozzle coöperating with the reverse vanes, substantially as set forth.
- 65 2. In an elastic-fluid turbine, the combination with two or more sets of movable direct vanes and intermediate guide-passages

through which the fluid passes in succession for producing forward motion, of two or more sets of movable reverse vanes and intermediate guide-passages through which the fluid passes in succession for producing backward motion, and an expansion-nozzle coöperating with the reverse vanes, substantially as set forth.

3. In an elastic-fluid turbine, the combination with movable direct vanes for producing forward motion, of two or more sets of movable reverse vanes and coöperating nozzles operating by stage expansion for producing backward motion, substantially as set forth.

4. In an elastic-fluid turbine, the combination with two or more sets of movable direct vanes and coöperating nozzles operating by stage expansion for producing forward motion, of two or more sets of movable reverse vanes and intermediate guide-passages through which the fluid passes in succession for producing backward motion, and an expansion-nozzle coöperating with the reverse vanes, substantially as set forth.

5. In an elastic-fluid turbine, the combination with two or more sets of movable direct vanes and coöperating nozzles operating by stage expansion for producing forward motion, of two or more sets of movable reverse vanes and coöperating nozzles operating by stage expansion for producing backward motion, substantially as set forth.

6. In an elastic-fluid turbine, operating by stage expansion, the combination with two or more separate wheel-chambers connected in succession, of two separate sets of movable vanes in each wheel-chamber, one for forward and the other for backward motion, and two sets of delivery-nozzles coöperating with the two sets of vanes, substantially as set forth.

7. In an elastic-fluid turbine, operating by stage expansion, the combination with two or more separate wheel-chambers connected in succession, of two separate sets of movable vanes in each wheel-chamber, one for forward and the other for backward motion, and two sets of expansion-nozzles coöperating with the two sets of vanes, substantially as set forth.

8. In an elastic-fluid turbine, operating by stage expansion, the combination with two or more separate wheel-chambers connected in succession, of two separate sets of movable vanes in each wheel-chamber, one for forward and the other for backward motion, two sets of delivery-nozzles coöperating with the two sets of vanes, and means for cutting off the flow of fluid simultaneously through the two or more delivery-nozzles of each set, substantially as set forth.

9. In an elastic-fluid turbine, operating by stage expansion, the combination with two or more separate wheel-chambers connected in succession, of two separate sets of movable vanes in each wheel-chamber, one for forward and the other for backward motion, two

sets of delivery-nozzles coöperating with the two sets of vanes, and means for cutting off the flow of fluid simultaneously through the two or more delivery-nozzles of each set and for coincidently opening the delivery-nozzles of the other set, substantially as set forth.

5 10. In an elastic-fluid turbine, the combination with unsymmetrically-curved vanes for producing forward motion and symmetrically-curved vanes for producing backward

motion, of nozzles for delivering elastic-fluid jets to such vanes separately, substantially as set forth.

This specification signed and witnessed this 26th day of July, 1897.

CHARLES G. CURTIS.
